BOTTLE

David G. Hills, Hartford, Conn., assignor to Plax Corporation, West Hartford, Conn., a corporation of Delaware

Application July 1, 1953, Serial No. 25,748

Term of patent 14 years

(Cl. D58—25)

To all whom it may concern:

Be it known that I, David G. Hills, a citizen of the United States, residing at Hartford, county of Hartford, State of Connecticut, have invented a new, original, and ornamental Design for a Bottle, of which the following is a specification, reference being had to the accompanying drawing, forming a part hereof.

Fig. 1 is a top plan view of a bottle, showing my new design;

Fig. 2 is a side elevational view of the bottle;

Fig. 3 is a rear elevational view of the bottle;

Fig. 4 is a fragmentary cross-sectional view taken on the line 4—4 of Fig. 2; and

Fig. 5 is a fragmentary cross-sectional view taken on line 5—5 of Fig. 2.

I claim:

The ornamental design for a bottle, substantially as shown.

DAVID G. HILLS.
